UNITED STATES PATENT OFFICE.

MARTIN GOLDBECK, OF KANSAS CITY, MISSOURI.

INTERNAL-COMBUSTION ENGINE.

1,304,039.

Specification of Letters Patent. Patented May 20, 1919.

Application filed March 26, 1918. Serial No. 224,816.

To all whom it may concern:

Be it known that I, MARTIN GOLDBECK, a citizen of the United States, at present residing at Kansas City, in the county of Jackson and State of Missouri, have invented new and useful Improvements in Internal-Combustion Engines, of which the following is a specification.

My invention, which relates to the art of internal combustion engines, has for its principal object to provide an engine of the rotary valve type, which will be practical and workable and in which adequate and practical provision is made for the proper lubrication of the moving parts of the valve structure and in which the parts are so designed and related that they may be readily reached for examination or repairs.

Another object of my invention is to provide a rotary valve engine with a detachable cylinder head, the same being so designed that by simply removing the cylinder head, the valve will be exposed and may be taken out as a unit to expose the valve seats.

A further object is to provide the engine with removable valve seat plugs of such design and construction that they may be easily lifted out so as to provide a large passageway into the combustion chamber, whereby the removal of carbon from the combustion chamber walls and from the piston head can be conveniently effected.

It has also been an object of the invention to provide a removable-cylinder-head-rotatable-valve engine of such construction that the intake ports are cast in the cylinder block and the exhaust ports are cast in the head block so that in removing the head for the purpose of cleaning out the carbon or for other reasons, no disconnection of the intake manifold or disturbance of the carbureter connections need be made and the exhaust manifold can be removed as a unit with the cylinder head, thereby reducing the time and labor necessary to overhaul the engine.

Again it has been one of the objects of my invention to make provision for keeping a gas tight contact between the valve seat plugs and the valve and between the seat plugs and the walls of the cylinder bores in which they fit so as to maintain compression as well as to provide for uniform suction on the intake stroke.

My invention provides means whereby the

internal pressure on the valve seat plugs may be, at all times, positive and even, so that the seat will be free to make gas tight contact with the valve, especially during the compression and working strokes. 60

Furthermore, it has been the object of the invention to provide a rotary valve engine in which the design of the parts is so made that the valve and valve seat elements are self-grinding. 65

Another object of the invention is to provide for the effective distribution of lubricant over the bearing surfaces of the valve and to provide a bearing structure for the valve which is so designed that the cylinder 70 head may be removed without disturbing the position and security of the valve, if desired.

With other objects in view which will be apparent to those skilled in the art, the invention includes those novel details of construction, combination and arrangement of parts, all of which will be first fully described and then be specifically pointed out in the appended claims, reference being had 80 to the accompanying drawings, in which:

Figure 1 is a side elevation and part section of a four cylinder engine embodying my invention.

Fig. 2 is an enlarged vertical longitudinal 85 section (a part being broken away) of the cylinder block and head parts, etc., of an engine embodying the invention.

Fig. 3 is an enlarged detail view of a portion of the invention. 90

Fig. 4 is a cross section on the line 4—4 of Fig. 3.

Fig. 5 is a cross section on the line 5—5 of Fig. 3.

Fig. 6 is a cross section on the line 6—6 95 of Fig. 3.

Fig. 7 is a detail perspective view of one of the valve seat plugs.

Fig. 8 is an inverted plan view of one of the lubricant distributing plates. 100

Fig. 9 is a plan view of the valve.

Fig. 10 is an inverted plan view of the cylinder head.

Fig. 11 is a plan view of the top of the cylinder block. 105

Fig. 12 is a cross section showing the valve seat, the valve, the lubricant distributing plate and the cylinder head separated and showing the facility with which the several parts may be assembled. 110

Figs. 13 to 16 inclusive are vertical cross sections through the respective cylinders showing the cycle of operation.

In the drawings in which like numerals and letters of reference indicate like parts in all of the figures, 1 represents the crank casing, 2 the crank shaft, 3 the connecting rods, 4 the oil pump, 5 the oil sump, 6 the oil baffle, 7 the main oil distributing duct 10 and 8 the pistons, all of which may be of any approved construction, as *per se* they form no part of the present invention claimed.

9 designates the cylinders which are preferably cast *en bloc* and are water jacketed as at 10. They also have compression spaces 11 and a head wall 12 which is of a stepped form in end elevation or vertical cross section so as to provide two surfaces 13—13 in 20 different horizontal planes, which are machined to receive the corresponding surfaces 34—34 of the cylinder head.

The head wall 12 also has a concaved valve seat surface 16, while the removable cylinder head is provided with a similar valve seat surface 34* in its wall 32.

The cylinder head-wall has shoulders 14 and 15 and the wall of the cylinder head is similarly shouldered, where necessary, to 30 fit the cylinder head-wall.

The intake ports 17 are preferably cast integrally with the cylinders, while the exhaust ports 36 are cast with the cylinder head, the head being water jacketed as at 33.

35 It will be observed that the cylinder head-wall is located some distance above the compression space 11 and it has bores 18—20 for each cylinder, which bores have seats 19 and 21 for the valve seat plug 22 which constitutes one of the features of my invention.

The plug 22 is preferably cylindrical and has a valve seat concavity 23 registering with the surface 16*. The surface 23 does not extend the full diameter of the plug 22 45 but provision is made for flat surfaces

24—24 at the top of the plug which are in register with the intake and exhaust ports respectively, the purpose of which will presently appear. The plug 22 is provided 50 with the passage 25 into the combustion chamber, the wall of the passage 25 being designed to merge with the wall of the combustion chamber, as clearly indicated in Fig. 3. The plug 22 has a reduced portion

55 26 and a beveled seat 27 to coöperate with the walls 20—21 of the cylinder head-wall-bore and the plug is provided with a suitable gasket 31 which rests between the shoulders 19 and 30. The plug is also provided with a packing ring groove 28 in which a piston ring of the usual construction is located.

Suitable gaskets 35 are provided between the opposing surfaces of the cylinder head-65 wall and the cylinder head.

36 designates the exhaust ports which are preferably cast integrally with the cylinder head, the head having recesses 37 adjacent to the ports 36 to receive the projecting part 39 of the lubricant distributing plate 40, 70 which plate 40 rests on the cylinder head and embraces the valve from the bottom of the exhaust port to the top of the intake port, as best shown in Fig. 6 of the drawings. The plates 40 are set in recesses 41 in the wall of the cylinder head and are held in contact with the valve 45 by springs 43 secured at 44 in recesses 42 in the cylinder head.

The valve 45, the construction of which is 80 best indicated in Figs. 3, 6 and 9, consists of a cylindrical or rod-like body having suitably disposed ports 46 located by recesses in the periphery of the valve and the valve is provided with an axial bore 51 through which the lubricant from the duct 7 is fed and distributed through lateral ducts or leads 53 to the periphery of the valve, the location of the leads 53 being such that the distribution of the lubricant will occur 90 in an annular path, crossing the valve engaging part of the plug 22 to the line of contact between the plug and the cylinder bore, so that lubricant may be fed between the plug 22 to the cylinder bore to effect a 95 gas tight seal.

Furthermore, the plate 40 is provided with suitably disposed lubricant distributing grooves 40*, see Fig. 8, into which the lubricant is fed from the leads 53 and distributed over the contacting surface of the valve 45 and plate 40, such of the lubricant as feeds endwise past the plate 40 functions to lubricate the valve surface in the space between adjacent plates 40.

47 designates the trunnion or bearing ends of the valve 45, against the front one of which is formed a collar 48, from which the end 49 on which the valve gear 63 is located, projects.

The valve is driven through a silent chain 64 passing over the gear 63 and a gear on the crank shaft. While I prefer this method of driving the valve, yet it should be understood that any of the other standard methods of practice may be employed in lieu thereof.

The valve 45 is counterbored, at one end, at 50 to receive the end of the duct 7 by which lubricant is delivered into the duct 51, 120 a gland 56 on the cap plate 54 serving to effect a lubricant tight joint, the plate 54 being secured at 55 over the end of the valve structure to the cylinder and the cylinder head units.

57 and 58 designate the two halves of the bearings for each end of the valve 45 in which bearings, the bearing portions 47 of the valve are journaled, there being oil leads 52 from the ducts 51 to the respective bear- 130

ing surfaces. The bearings 57 and 58 are secured together and to the cylinder structure by cap screws 59 that pass through lugs on the bearings 57 and 58 and are tapped at 5 71 into the cylinder head-wall. The cylinder head has recesses 60 for the screw heads so that the cylinder head can be removed without disturbing the screws 59 and in order that the impacting blows on the sections 58 10 may be distributed to the cylinder head and thus relieve the screws 59, screws 61 with interposed fiber or other hard disks 62 are provided, whereby, regardless of any variation in the thickness of the cylinder head 15 gasket, the screws 61 can be tightened down to transmit the impacts from the bearing sections 58 to the cylinder head and thus distributing the same therethrough, thereby adding to the life of the engine and aiding 20 in maintaining the gas tight contact necessary between the valve and valve seats.

65 designates the water passages in the cylinder head and in the cylinder which register with one another to permit a circulation 25 of water from the cylinder jacket to the head jacket, as is the usual practice, and 66 designates the screw holes in which the screw bolts 72 that screw the cylinder head to the cylinder are tapped. 30 67 designates the intake manifold and 68 the intake from the carburetor (see dotted lines Fig. 11) and 69 designates the passage-way that communicates with the intake manifold 67, at its end, and a pair of adjacent intake ports for the adjacent cylinders, while 70 designates the exhaust manifold which is common to all of the exhaust 35 ports.

The cycle of operation is indicated in Figs. 40 13 to 16, inclusive, the parts being positioned in Fig. 13 just at the commencement of the suction stroke, the exhaust port just having closed and the intake port being about to open.

45 Fig. 14 indicates the position of parts at the end of the suction stroke, the exhaust port being closed and the intake port just about closed.

Fig. 15 shows the position of the parts on 50 completion of the compression stroke and just at the time the explosion occurs.

Fig. 16 indicates the position of the parts at the end of the working stroke of the piston, the exhaust port beginning to open and 55 opening fully as the piston rises to expel the charge.

It will be noticed from the foregoing that 60 by constructing the engine parts, especially the valve, the cylinder head, the head end of the cylinders and the valve seat members, as shown and described, and providing the special lubricating arrangement that I have, provides, a practical and, I believe, effective construction for the purposes intended.

65 It will be noted that on the compression

and working strokes of the piston, the valve seat members will be held up against the valve with sufficient pressure contact to maintain a gas tight engagement and prevent leakage which would cause loss of compression and loss of power. 70

Furthermore, by constructing the seat member, as shown and described, the seat will be held against the valve on the suction stroke also and the packing will insure a gas 75 tight connection between the valve seat member and the cylinder.

It will also be noted that the valve engaging surface of the seat member does not extend the full diameter of the valve seat 80 member and that small segments of the seat are exposed in both ports. This is done so that the internal pressure may, at all times, be positive and, furthermore, the seat does not have to be milled to a feather edge, 85 which would perhaps, be impractical.

It is also to be noted that the lower part of the seat is cut away on a line approximately 45 degrees with the vertical side wall. This angle may, of course, be varied, and although I have arranged the inside area in such a manner that there shall not be too much pressure on the seat so that it would exert a drag on the valve rotor, by increasing this angle to 90 degrees, the inside exposed area will be lessened and pressure reduced. 90

It will also be noted that the valve rotor is entirely free floating, except for the contact with the valve seat and the slight drag of 100 the lubricating plate.

The rest of the housing should be made with not less than 0.0015 inch clearance on the bottom side and about 0.0025 inch clearance on top; any slight variation in location 105 of the detachable head will make no difference, since the bearings for the valve are secured to the cylinder casing and by using the reinforcing screw on hard rubber or fiber pad, the cylinder head absorbs most of the 110 pressure.

In practice, I prefer to use babbitt lined bronze bearings for the valve owing to the pounding these bearings will receive.

It will be also noted that by my design, 115 ample port area is provided in the valve and valve seat member, to render the action of the engine most effective and efficient.

Of course, the engine can be made in any desired size with any desired number of 120 cylinders and I, of course, do not wish to be limited to any particular details of construction beyond what is made necessary by the prior art and the scope of the appended claims. 125

While I have described the preferred construction of the invention, I also desire it understood that numerous changes in the construction, arrangement, proportions of parts, &c. can be made without departing 130

from the invention or the scope of the appended claims.

What I claim is:—

1. In an internal combustion engine, a cylinder having a head-wall provided with a bore communicating with the piston chamber, a valve seat plug in said bore, said plug having a passage, a cylinder head secured over the cylinder head-wall, inlet and exhaust ducts adapted to communicate with said bore and a rotatable valve between the cylinder head and the head-wall and co-operating with said ducts and said valve seat plug for controlling the admission and exhaust functions of the engine, said plug having surface portions exposed to atmospheric pressure through the inlet and exhaust ducts.
2. In an internal combustion engine, a cylinder having a head-wall provided with a bore in communication with the piston chamber, a valve seat plug in said bore, said plug having a passage, a cylinder head secured over the cylinder head-wall, inlet and exhaust ducts adapted to communicate with said bore and a rotatable valve between the cylinder head and the head-wall and co-operating with said ducts and said valve seat plug for controlling the admission and exhaust functions of the engine, and means for lubricating the relatively movable surfaces of said valve and said seat plug, said plug having surface areas exposed to the atmosphere through the inlet and exhaust ducts.
3. In an internal combustion engine, a cylinder having a head-wall provided with a bore communicating with the piston chamber, a valve seat plug in said bore, said plug having a passage, a cylinder head secured over the cylinder head-wall, inlet and exhaust ducts adapted to communicate with said bore, a rotatable valve between the cylinder head and the head-wall and co-operating with said ducts and said valve seat plug for controlling the admission and exhaust functions of the engine, and means for maintaining atmospheric pressure against a predetermined area of one end of said plug, said valve having an oil duct with leads to the surface whereby to lubricate said valve.
4. In an engine of the class described, a cylinder having a piston chamber and a head-wall with a bore through the head-wall, said cylinder having an intake port above the bore, a cylinder head detachably fitted over said cylinder head-wall and having an exhaust port, a rotatable valve interposed between the cylinder head and cylinder head-wall to control the passage between said bore and said port, said head and said head-wall respectively having valve receiving recesses for said valve, and a removable valve seat plug held in said bore and itself having a passage controlled by said valve, said plug having a predetermined area exposed to atmospheric pressure.
5. In an engine of the class described, a cylinder having a piston chamber and a head-wall with a bore through the head-wall, said cylinder having an intake port above the bore, a cylinder head detachably fitted over said cylinder head-wall and having an exhaust port, a rotatable valve interposed between the cylinder head and the cylinder head-wall to control the passage between said bore and said port, said head and said head-wall respectively having valve receiving recesses for said valve, a removable valve seat plug held in said bore and itself having a passage controlled by said valve, said plug having a predetermined area exposed to atmospheric pressure, and means for effecting a gas-tight engagement between said plug and said valve and between said plug and the wall of the bore in which it is fitted.
6. In an engine of the class described, a cylinder having a piston chamber and a head-wall with a bore through the head-wall, said cylinder having an intake port above the bore, a cylinder head detachably fitted over said cylinder head-wall and having an exhaust port, a rotatable valve interposed between the cylinder head and the cylinder head-wall to control the passage between said bore and said port, said head and said head-wall respectively having valve receiving recesses for said valve, a removable valve seat plug held in said bore and itself having a passage controlled by said valve, said plug having a predetermined area exposed to atmospheric pressure, means for effecting a gas-tight engagement between said plug and said valve and between said plug and the wall of the bore in which it is fitted, said last named means including mechanism for feeding oil through said valve and distributing the same over the relatively movable surfaces.
7. In an engine of the class described, a cylinder having a piston chamber and a head-wall with a bore through the head-wall, said cylinder having an intake port above the bore, a cylinder head detachably fitted over said cylinder head-wall and having an exhaust port, a rotatable valve interposed between the cylinder head and the cylinder head-wall to control the passage between said bore and said port, said head and said head-wall respectively having valve receiving recesses for said valve, a removable valve seat plug located in said bore, said plug having a passage controlled by said valve, said plug having a predetermined area exposed to atmospheric pressure, a packing ring carried by said plug to engage

the wall of the bore, and means for supplying lubricant to the relatively movable surfaces of the valve and plug.

8. In an engine of the class described, a cylinder having a piston chamber and a head-wall with a bore through the head-wall, said cylinder having an intake port above the bore, a cylinder head detachably fitted over said cylinder head-wall and having an exhaust port, a rotatable valve interposed between the cylinder head and cylinder head-wall to control the passage between said bore and said port, said head and said head-wall respectively having valve receiving recesses for said valve, said cylinder head having a chamber, a lubricant distributing plate in said chamber, and means holding said plate to embrace said valve, and means for supplying lubricant to the relatively movable surfaces of said valve and plug.

9. In an engine of the class described, a cylinder having a piston chamber and a head-wall with a bore through the head-wall, said cylinder having an intake port above the bore, a cylinder head detachably fitting over said cylinder head-wall and having an exhaust port, a rotatable valve interposed between the cylinder head and cylinder head-wall to control the passage between said bore and said port, said head and said head-wall respectively having valve receiving recesses for said valve, a removable valve seat plug located in said bore and having a passageway controlled by said valve, a packing ring around said plug to engage the wall of the bore, said cylinder head having a chamber, a lubricant distributing plate in said chamber, and means holding said plate to embrace said valve, and means for supplying lubricant to the relatively movable surfaces of said valve and plug.

10. In an engine of the class described, a cylinder having a piston chamber and a head-wall with a bore through the head-wall, said cylinder having an intake port above the bore, a cylinder head detachably fitted over said cylinder head-wall and having an exhaust port, a rotatable valve interposed between the cylinder head and cylinder head-wall to control the passage between said bore and said port, said head and said head-wall respectively having valve receiving recesses for said valve, bearing members for said valve, means removably securing said bearing members to the cylinder whereby said head can be removed without disturbing the position of said valve with relation to the cylinder, and means carried by the cylinder head to engage said valve bearing whereby the impact of the valve on the bearing may be transmitted to the head.

11. In an engine of the class described, a

cylinder having a piston chamber and a head-wall with a bore through the head-wall, said cylinder having an intake port above the bore, a cylinder head detachably fitted over said cylinder head-wall and having an exhaust port, a rotatable valve interposed between the cylinder head and cylinder head-wall to control the passage between said bore and said port, said head and said head-wall respectively having valve receiving recesses for said valve, said cylinder head having a chamber, a lubricant distributing plate in said chamber, means holding said plate to embrace said valve, means for supplying lubricant to the relatively movable surfaces of said valve and plug, said distributing plate having a port to register with said exhaust port and extending around over the valve from the exhaust port to the intake port.

12. In an engine of the class described, a cylinder having a piston chamber and a head-wall with a bore through the head-wall, said cylinder having an intake port above the bore, a cylinder head detachably fitted over said cylinder head-wall and having an exhaust port, a rotatable valve interposed between the cylinder head and cylinder head-wall to control the passage between said bore and said port, said head and said head-wall respectively having valve receiving recesses for said valve, a removable valve seat plug located in said bore and having a passageway controlled by said valve, packing interposed between the plug and the wall of the bore, said cylinder head having a chamber, a lubricant distributing plate in said chamber, and means holding said plate to embrace said valve.

13. In an engine of the class described, a cylinder having a piston chamber and a head-wall with a bore through the head-wall, said cylinder having an intake port above the bore, a cylinder head detachably fitted over said cylinder head-wall and having an exhaust port, a rotatable valve interposed between the cylinder head and cylinder head-wall to control the passage between said bore and said port, said head and head-wall respectively having valve receiving recesses for said valve, a removable valve seat plug located in said bore and having a passageway controlled by said valve, packing interposed between the plug and the wall of the bore, said cylinder head having a chamber, a lubricant distributing plate in said chamber, means holding said plate to embrace said valve, and means for supplying lubricant to said distributing plate through said valve.

14. In an internal combustion engine, a cylinder having a head-wall provided with a port communicating with the piston chamber, a valve seat plug in said port, said plug

having a passage, a cylinder head secured over the cylinder head-wall, the cylinder head and the cylinder head-wall having stepped portions in engagement with one another, the cylinder head-wall having an inlet duct above the seat plug and the cylinder head having an exhaust duct above the seat plug, said seat plug having end surfaces

adjacent to the cylinder head exposed to atmosphere pressure through said ducts, and a rotatable valve located between the cylinder head and the head-wall and coöperating with said ducts and said valve seat plug for controlling the admission and exhaust functions of the engine.

MARTIN GOLDBECK.
